CLAIM

The ornamental design for a stand for an audio device as shown and described.

DESCRIPTION

FIG. 1 is a front elevation view of a stand for an audio device showing the new design.

FIG. 2 is rear elevation view thereof.

FIG. 3 is a top plan view thereof.

FIG. 4 is a bottom plan view thereof.

FIG. 5 is a right side view thereof.

FIG. 6 is a left side view thereof; and,

FIG. 7 is a perspective view thereof.

The broken lines depict portions of the stand for an audio device that form no part of the claimed design; the stand for an audio device is shown with a symbolic break in FIGS. 1, 2, 5, 6, and 7. The appearance of any portion of the stand for an audio device between the break lines forms no part of the claimed design.
